David S. Murphy. INVENTOR
BY
H. G. Burns ATTORNEY

UNITED STATES PATENT OFFICE.

DAVID S. MURPHY, OF FORT WAYNE, INDIANA.

HEATING APPARATUS.

Application filed January 27, 1923. Serial No. 615,233.

To all whom it may concern:

Be it known that I, DAVID S. MURPHY, a citizen of the United States of America, and resident of Fort Wayne, in the county 5 of Allen and State of Indiana, have invented certain new and useful Improvements in Heating Apparatus, of which the following is a specification.

This invention relates to improvements in 10 heating apparatus and the objects thereof are: first, to utilize the heat that ordinarily passes from a stove through the smoke pipe and is wasted; and second, to provide means for the reduction in the amount of smoke 15 that ordinarily is caused by incomplete combustion of the fuel.

These objects are accomplished by the construction illustrated in the accompanying drawings, in which:—

20 Fig. 1 is a side elevation of an apparatus embodying the invention, portions being broken away and in section;

Fig. 2 is a plan view projected from Fig. 1; and

25 Fig. 3 is a vertical section of a heat trap of modified form.

The characters appearing in the description refer to parts shown in the drawings and designated thereon by corresponding 30 characters.

The invention comprises a stove 1 that is located in a drum 2 which is of a size that affords a space 3 between its inner walls and the shell 4 of the stove, the bottom of 35 the drum being open. The stove has a smoke pipe 5 that extends through the top of a closed box 6 and terminates at a point near the bottom of the box. A second smoke pipe 7 extends through the top of the 40 box and terminates also at a point near the bottom of the box. Upon each pipe 5 and 7 is arranged an adjustable extension 8 that is provided with a rod 9 by means of which the extension may be vertically 45 adjusted. The rod has a foot 10 which limits the movement of the extension by coming into contact with the bottom of the box when the extension is moved downward, and by coming into contact with the lower 50 end of the smoke pipe when the extension is moved upward. The box 6 is located

in a drum 11 which is of a size that affords a space 12 between its inner walls and the box 6, the drum being open at its lower end. Each of the pipes 5 and 7 extends through 55 the top of the drum, the pipe 7 being intended for connection with a chimney (not shown).

That portion of the pipe 5 that extends from the drum 2 to the other drum 11 is 60 enclosed by a jacket 13 of a size that affords a space 14 between its inner wall and the pipe 5, and the pipe is provided with a damper 15. The jacket 13 has openings 16 near its ends and a pipe 17 has connection 65 at one end with the jacket and at its other end with the stove at a point beneath the grate 18.

That portion of the smoke pipe 7 that extends from the drum 11 to the chimney 70 is enclosed by a jacket 19 that is of a size that affords a space 20 between its inner wall and the pipe, the jacket being provided with a number of openings 21 and 22.

The drum 2 has a pipe connection 23 at 75 its top with a hot air pipe 24, and the drum 11 has also a pipe connection 25 at its top with said hot air pipe so that the heat from said drums may be conveyed by the hot air pipe to a point more or less remote. Around 80 the pipe 24 is a jacket 26 that is of a size that affords a space 27 between its inner wall and the pipe, and the jacket may have an extension 28 for similarly enclosing the connection 23.

While there is shown but one connection leading from the drum 2 it is the intention that additional connections may be provided when needed for conveying heat to various places. Such an additional pipe 29 is shown 90 in connection with the drum 11 at one end and with the pipe 24 at its other end. There is also shown in the top of the drum 11 a lid 30 that may be removed for the admission of heat from the drum directly into 95 the room in which the drum is located. In the side of the drum 11 is a door 31 located at a point higher than the box 6 so that articles may be heated by being placed through the door opening into the heat box 100 and the space in the upper part of the drum utilized as an oven. In the lower part of

the box is a hand-hole 32 through which access may be had to the box for the removal of accumulated products of combustion.

In the modification shown in Fig. 3 the smoke pipe 33 extends entirely through the upper part of the box 34 and has a branch 35 that extends down into the lower part of the box. The branch has upon its lower end a vertically adjustable extension 36 provided with an adjusting rod 37 as in the former instance.

In the operation of the invention the hot smoke from the stove passes through the smoke pipe 5 into the heat box 6 which becomes heated thereby, and the smoke thus relieved of a portion of its heat passes from the lower part of the box out through the smoke pipe 7 to the chimney. Also, the air in the space 14 in the jacket 13 becomes heated by the radiation of heat from the smoke pipe 5, the heated air from the jacket being conveyed by the pipe 17 to a point beneath the grate in the stove so that the air supplied to the fuel is initially heated by the fire that it supplies.

The air that is heated in the jacket 19 by the radiation of heat from the smoke pipe 7 may be conducted to points more or less remote by connecting pipes 22' with the openings 22 in the jacket.

The air in the space 27 in the jacket 26 becomes heated by the radiation of heat from the pipe 24 and is retained about the pipe 24 and its connection 23 so that the heat passing through the hot air pipe 24 is conserved therein. Where the heat is to be conveyed to a distant point, the pipe 24 and jacket 26 thereof are lengthened accordingly. In this manner the heat in the pipe 24 may be conducted a great distance.

The draft of smoke through the lower part of the heat box 6 from the pipe 5 into the pipe 7 may be regulated by raising or lowering the extensions 8, and when adjusted to the desired positions are held in place by means of corresponding set-screws 38 by which the rods 9 are secured.

In the modified form the interior of the box 34 becomes heated by radiation from the smoke pipe and its branch, and also by the hot smoke that may enter the box through the open extension 36. In this form the smoke pipe has connection as in the former instance with the stove and the chimney.

What I claim is:—

1. In combination with a stove, a drum having an open bottom and enclosing the stove, there being a space between the walls of the drum and the shell of the stove; a closed box; a second drum having an open bottom and enclosing said box, there being a space between the inner walls of the drum and box; a damper controlled

smoke pipe having connection at one end with the stove and its opposite end with the lower part of said box; a jacket enclosing the smoke pipe between said drums and having inlet openings; a pipe having connection with said jacket at one end and communication at its other end with said stove at a point beneath the grate thereof; a second smoke pipe having communication with the lower part of said box and extending up through said second drum to a suitable point for connection with a chimney; a second jacket enclosing that portion of the latter smoke pipe between the drum and chimney and having a series of openings therein; a hot air pipe having connections with both of said drums at the tops thereof; means for confining air about said hot air pipe; and an adjustable extension in said box for each of said smoke pipes.

2. In combination with a stove, an open bottomed drum surrounding the stove; a heat box having a pipe connection with the stove for the reception of hot smoke therefrom; a second open bottomed drum enclosing the heat box; a smoke pipe leading from the lower part of the heat box and extending through the top of said second drum to a suitable point for connection with a chimney; a jacket enclosing that portion of the smoke pipe between the drum and chimney and having a series of openings therein; a hot air pipe leading from the upper part of each drum; and an adjustable extension for said pipe connection and said smoke pipe located in the heat box.

3. In combination with a stove, a drum surrounding the stove and having an open bottom, there being a space between the walls of the drum and the shell of the stove; a smoke pipe for the stove; a jacket surrounding said smoke pipe and having openings therein, there being a space between the inner walls of the jacket and said smoke pipe; and a pipe connection between said jacket and with said stove at a point beneath the grate thereof.

4. In combination with a stove having a smoke pipe, a closed heat box arranged with said stove pipe extending thereto and terminating at a point near the bottom thereof; a second smoke pipe, one end of which extends into the heat box and terminates at a point therein near the bottom thereof; an open bottomed drum enclosing the heat box, there being a space between the inner walls of the drum and said heat box; means for the regulation of the passage of smoke through said heat box from one of said pipes to the other; and means having connection with the upper part of said drum for conveying heated air therefrom.

5. In combination with a stove, a closed

box; a smoke pipe having connection with the stove and extending through said box, said smoke pipe having a downwardly extending branch affording communication between said smoke pipe and the lower part of said box; and an adjustable extension for said branch.

In testimony whereof I affix my signature in presence of two witnesses.

DAVID S. MURPHY.
